MULTIPLE TUBE RADIATOR FORCED CIRCULATION AIR HEATING FURNACE

Allan Bryson Carswell, Ottawa, Ontario, Canada

Application May 13, 1948, Serial No. 26,789

6 Claims. (Cl. 126—110)

1

This invention relates to improvements in a furnace and, especially, to one having increased heat transfer areas and a more efficient routing of the products of combustion from the fire pot to the emerging smoke pipe.

Among the principal objects of the invention are to provide a novel furnace structure that will yield up a higher percentage of the total heat of combustion, enable the extraction of substantially all the heat from the products of combustion reducing the temperature of the output of normally very hot flue gases to near room temperature, and in which the essential parts of the furnace are so arranged as to afford ready access for cleaning and servicing that the unit may be easily maintained in a condition for peak performance.

A further object of the invention is to provide a heat transferring bank of finned smoke tubes removably mounted in the furnace to allow of replacement as a single unit.

It is further within the province of the invention herein disclosed to provide a hot air furnace of generally simplified and improved design, substantial and durable structure and enhanced operating efficiency and economy that is capable of manufacture at a relatively reasonable cost.

To the accomplishment of these and related objects as shall become apparent as the description proceeds, the invention resides in the construction, combination and arrangement of parts as shall be hereinafter more fully described, illustrated in the accompanying drawings, and pointed out in the claims hereunto appended.

The invention will be best understood and can be more clearly described when reference is had to the drawings forming a part of this disclosure wherein like characters indicate like parts throughout the several views.

In the drawings:

Figure 1 is a vertical longitudinal section through a furnace constructed in accordance with this invention;

Figure 2 is a vertical transverse section therethrough;

Figure 3 is a plan view, with one half sectioned;

Figure 4 is a rear elevation with the lower left portion broken away; and

Figures 5 and 6 are details of the heat radiating fin, being an elevation and section respectively.

With an elongated rectangular casing 1 a fire pot 2 and dome 3 are arranged somewhat forwardly of a central position. Across the front of the dome and in open communication with it is

2

a transverse horizontal chamber 4. Across the rear of the furnace, level with the dome and front chamber 4, and spaced somewhat behind the rear of the dome is a smoke outlet manifold 5 from which the usual smoke pipe 6 emerges.

Joining the front chamber 4 and the rear smoke manifold 5 are two banks of finned tubes 7, one on either side of the fire pot dome 3. Just to the rear of this dome a vertical transverse bulkhead or partition 8 divides the furnace casting 1 into fore and aft sections with half or more of the tube banks lying in the forward part. It will be seen the top of the casing 1 is open as this instant invention is not concerned with either the source or eventual distribution of the air. However, the partition 8 marks the division between the cold air inlet 9 and the hot air outlet 10.

Below the rear smoke manifold 5 and the after part of the tube banks 7 the air passageway or route 11 passes through filter pads 12 then enters opposite sides of a motor driven fan 13 in a fan housing 14 in the lower rear of the furnace casing thence under the partition 8 into the forward section of the furnace where it encircles the fire pot and dome and rises through the banks of finned smoke tubes 7 to pass out through the outlet 10 in the open top of the forward section.

Though my furnace may be adapted to any kind of fuel or firing, Figure 1 shows a gun type oil burner 14 in a closed off compartment the lower front protected by a removable louvered front closure 15. The upper part of the walls and sloping part of the top of the front section of the casing is insulated as indicated at 16 and in addition to a door 17 affording access to the fire pot, dome and front transverse chamber 4, a hinging baffle guard 18 is suspended.

Preferably the entire furnace is of all-welded steel construction and the outer air-engaging surfaces of the dome 3 and front chamber 4 have radiating vanes or ribs 19 that serve also to strengthen the dome structure.

The banks of tubes 7 are each formed as a complete and removable unit. The multitude of small, relatively thin, equally spaced, parallel tubes 7a are carried by three panels 7b, 7c and 7d respectively and, provided with fireproof, air tight gaskets, are removably secured to flanges 20 at the front compartment, the partition 8 and the inner wall of the rear smoke manifold 5. On the back of the casing 1, in line with each bank of tubes 7 is a clean out door 21 of sufficient size

to allow for the installation and removal of a complete bank. Spaced longitudinally along the banks of tubes are thin, vertical, transversely extending sheet metal radiating fins $7e$ having perforations $7f$ to pass the fins, and the perforations flanged as at $7g$. The fin perforations have a tight, frictional engagement with the tubes so the expanding of the metal on heating increases the conductivity of the connection. Like all other joints in this furnace, the tubes are welded to the panels, especially $7b$ and $7d$, although the partition engaging panel $7c$ may be an enlarged fin.

The cross sectional area of the tubes $7a$ is such as to offer no obstruction to the flow of the products of combustion therethrough even with the greater surface frictional engagement encountered and being small and finned and of considerable length the gases flowing therethrough are able to give up almost completely of their heat units before emerging into the rear smoke manifold 5 . The down draft of incoming cold air entering through the open top 9 of the rear section passes over the rear ends of the already partly cooled banks of tubes $7a$, and is partially warmed while taking up most of the remaining heat of the flue gases in the tube banks. Thus the current of air is raised to a higher temperature than would otherwise be the case by contact with the ribbed fire box dome and the very hot front sections of the tube banks before leaving the front section furnace outlet 10 .

From the foregoing description taken in connection with the accompanying drawings, it will be manifest that an efficient and economical furnace is provided that will fulfill all the necessary requirements of such a device, but as many changes could be made in the above description and many apparently widely different embodiments of the invention may be constructed within the scope of the appended claims, without departing from the spirit or scope thereof, it is intended that all matters contained in the said accompanying specification and drawings shall be interpreted as illustrative and not in a limitative or restrictive sense.

Having thus described the invention, what I claim as new and desire to secure by Letters Patent is:

1. A furnace comprising a fire pot fueled from the front and dome surmounting the same, a transversely disposed chamber forward of said dome in communication therewith, a transversely disposed outlet manifold to the rear of said dome, removable banks of horizontal tubes on each side of said dome connecting said chamber and manifold and a casing therefor with an inlet at the upper rear portion and an outlet at the upper front portion thereof and having an air passage-way therethrough beginning over the rear of said banks of tubes and subsequently crossing the forward ends of said banks of tubes.

2. A furnace comprising an outer casing, a front fueled fire pot and surmounting dome therein forwardly of centre, a transversely disposed chamber in front of said dome centrally open thereto, a transversely disposed outlet manifold in the rear of said casing and spaced a distance back of said dome, a unitary removable bank of heat transfer tubes on each side of said dome connecting said chamber and said manifold, a vertical transverse partition in said casing extending across said casing from side to side

and downwardly from the top to a point spaced above the bottom thereof and disposed to the rear of said dome and a fan circulating air down the back of said partition and up the front; said casing having air inlet and outlet openings disposed respectively to the rear and front of said partition and both located above the lower edge thereof.

3. The combination with the structure set forth in claim 2, of a clean out door in the back of said casing in line with each of said banks of tubes and wherein said banks of tubes are each removable longitudinally through said doors as a unit, said banks of tubes having front and rear end panels in which the tubes are terminally welded and which panels are releasably joined to the front chamber and rear manifold respectively.

4. The combination with the structure set forth in claim 2, wherein each heat transferring bank of tubes consists of a plurality of elongated horizontal tubes, radiating fins spaced therealong and a panel on each end in which the tubes are terminally welded, said panels engaging respectively the front transverse chamber and rear transverse manifold.

5. The combination with the structure set forth in claim 2, wherein a heat transferring bank of tubes consists of a plurality of elongated horizontal tubes, radiating fins spaced therealong, formed of sheet metal and perforated to pass the many tubes of the bank, the perforations being of a size and flanged to have tight fitting engagement with the tubes.

6. An all-welded steel furnace comprising an outer shell or casing open to the top, a vertical, transverse partition dividing said casing longitudinally into front and rear sections with an opening through the bottom thereof, an air circulating fan directed forwardly through said partition opening so a current of air is drawn into the casing through the open top of the rear section, passed under said partition and expelled through the open top of the front section, a fire pot and dome in said casing forwardly of said partition, a transversely disposed chamber across the front of and in communication with said dome being open thereto throughout its height for the full width of said dome, a transversely disposed outlet manifold in the rear of said casing and spaced a distance back of said partition and a bank of finned heat transfer tubes on each side of said dome connecting said front chamber and said rear manifold, said banks being longitudinally removable through the back of said casing and sealed where they fasten to said chamber and manifold with fireproof air-tight gaskets.
